United States Patent Office.

AUSTIN Z. MASON AND RICHARD B. ROBBINS, OF ADRIAN, MICHIGAN,
ASSIGNORS TO RICHARD B. ROBBINS.

Letters Patent No. 82,014, dated September 8, 1868.

IMPROVED VISE.

The Schedule referred to in these Letters Patent and making part of the same.

TO ALL WHOM IT MAY CONCERN:

Be it known that we, AUSTIN Z. MASON and RICHARD B. ROBBINS, of Adrian, in the county of Lenawee, and State of Michigan, have invented a new and useful Improvement in Bevel Vise-Jaws; and we do hereby declare that the following is a full, clear, and exact description of the construction and operation of the same, reference being had to the annexed drawings, and to the letters of reference marked thereon, making a part of this specification, like letters referring to like parts.

The nature of our invention consists in a new, simple, and practical mode of constructing bevel vise-jaws, so arranged that they may be used either as a positive parallel jaw, or be turned at any desired angle to clamp wedge-shaped pieces, the same being intended as an improvement on Austin Z. Mason's improvement in vise, patented April 28, 1868, patent No. 77,390.

In the drawings—

Figure 1 represents a view of our improved vise-jaw attachments, taken on a horizontal line at right angles with the vise-screw, the jaw being represented as placed parallel, to clamp a parallel piece.

Figure 2 represents a view of the vise-jaw from the same direction, with the movable jaw turned at an angle, to clamp a wedge-shaped piece.

Figure 3 is a perspective view of the washer-plate B and adjustable ring C.

Figure 4 is a perspective view of the semispherical bilge D, face-plate D', and wooden disk E.

Figure 5 represents a side view of the two parts shown in fig. 3.

Figure 6 represents a side view of the semi-annular ring K.

In the main, this invention is similar to that of Mason's patent vise previously mentioned, differing from it only as herein set forth and described.

The ring C has, on its back side, a short hub, to fit into and keep it central on the plate B, and on the other side, the ring C is faced off by two equally-inclined planes x y, whose obliquity to the plane of the back side of the ring is equal to the greatest possible angle to which the jaw is designed to turn.

The opening through the centre of the ring is concave, so as to turn or rock upon the spherical bilge D of the face-plate D', the ring having no handle.

To the face-plate D' is attached, if desirable, a wooden disk, E, to adhere to the surface of the piece clamped.

On opposite sides of the spherical bilge D are ribs m and n, (fig. 4,) to fit into corresponding recesses m' and n', (fig. 3,) so as to allow a rocking and prevent a swivel movement of the face-plate D' upon the ring C, thus causing the ring C to turn whenever the face-plate D' is turned.

The ring C is also provided with projecting stops c and e, which strike against similar stops a and b of the washer-plate B. These stops are designed to prevent the ring C, and, therefore, the face-plate D', from revolving more than one-fourth of a circumference, and in order to secure the requisite strength, the two stops c and e may be combined in one, and the two stops a and b made any desirable size.

The spherical bilge D, ring C, washer-plate B, and movable jaw A, are all held together in working order, as shown in fig. 1, by any suitable bolt.

It is evident now, from the description already given, that when thus constructed and brought into working order, the operator may, by grasping the face-plate E with the hand, turn it and the ring C simultaneously one-fourth of a circumference, and may rock it one way and the other, so as to receive and clamp a wedged or parallel piece.

If, now, he wishes to convert it into a positive parallel jaw, he has only to drop the semi-annular ring K, having parallel sides, into position, as shown in fig. 1, the ends of the ring K resting on the projecting stops a and b. By this means, the upper half of the face-plate D' has a positive or solid bearing against the ring K, and the ring, a like bearing against the washer-plate B, thus furnishing the mechanic with a safe, simple, and solid parallel vise-jaw. By removing the ring K, and properly adjusting the face-plate D', any wedge-shaped piece may, with equal facility, be clamped and held in position.

Having thus described our invention, what we claim as new, and desire to secure by Letters Patent, is—

1. In combination with the ring C, constructed with the oblique faces *x* and *y*, the recesses *m'* and *n*, and one or more projecting stops *c* and *e*, to prevent it from turning more than one-fourth of a circumference, the whole constructed in the manner substantially as set forth and described.
2. The spherical bilge D, with one or more ribs *m* and *n*, or their equivalents, in combination with the ring C, constructed substantially as set forth and described.
3. The semi-annular ring K, in combination with the ring C and washer-plate B, substantially as described.

RICHARD B. ROBBINS,
AUSTIN Z. MASON.
